UNITED STATES PATENT OFFICE.

WILLIAM MOUNT BISHOP, OF BEAUFORT, SOUTH CAROLINA.

ADVERTISING DEVICE.

Application filed August 11, 1922. Serial No. 581,183.

To all whom it may concern:

Be it known that I, WILLIAM M. BISHOP, a citizen of the United States, residing at Beaufort, in the county of Beaufort and 5 State of South Carolina, have invented new and useful Improvements in Advertising Devices, of which the following is a specification.

My present invention has reference to an 10 advertising device.

In carrying out my invention it is my purpose to produce an outdoor advertising device that includes a cabinet in which there are arranged hand drawn cartoons and pictures 15 showing black and white, without coloring in the daytime, and colored at night.

It is also my purpose to produce an advertising device that includes a cabinet comprising front and back glass plates with a 20 mat interposed therebetween, the said mat having cut-out portions of varying designs that receive therein sheets each of which having a line view of an object on one face and a colored view on its opposite face arranged 25 complementary with respect to the first mentioned view, the first mentioned view being disclosed in the daytime, while a transmitted light is arranged to the rear of the last mentioned view so that a complete 30 change of the drawing is effected in the night time.

The foregoing, and many other objects which will present themselves as the nature of the invention is better understood, may 35 be accomplished by a construction and arrangement of parts such as is disclosed by the drawings which accompanying and form part of this application.

In the drawings:—

40 Figure 1 is a front elevation of the advertising device as it will be shown in the daytime.

Figure 2 is a sectional view taken on line 2—2 of Figure 1.

45 Figures 3 and 4 are fragmentary views illustrating the front of the advertising or translucent sheet.

Figure 5 is a sectional view taken on line 5—5 of Figure 2.

50 Figures 6, 7 and 8 are fragmentary views illustrating the rear face of the translucent sheet.

My advertising device, as above stated is designed for outdoor use or it may be dis-

played within a show window, and comprises a cabinet designed to receive the front and rear glass plates 1 and 2 respectively and between these plates there is arranged a mat 3. The plates are slidably horizontal in suitable guides 4 secured at the upper and lower edges of the cabinet so that access may be obtained to the mat, or interior of the cabinet if desired. 55

The mat 3 is provided with differently shaped openings 5 and arranged in the rear of the mat and in contacting engagement therewith, there is a translucent sheet 6. This sheet has on its front face one, or a plurality of line drawings, as shown in Figures 3 and 4 of the drawings and which are 60 adapted to show through the openings in the mat. 65

The drawing refers to articles to be advertised, and suitable printed data also appears upon the said face of the sheets. The rear face of each sheet 6 has painted thereon a colored view 8, the views 8 being disposed directly to the rear of the line drawings 7. Preferably the colored views 8 are of different characteristics from the 70 line drawings so that an entirely different aspect is presented when electric bulbs 9, arranged at the rear of the cabinet, are 75 lighted. The bulbs are not lighted in the daytime, so that only the line drawings 7 are 80 lighted in the daytime, so that only the line drawings 7 are 85 on the translucent sheets 6 are offered to view. In the night time when the bulbs are lighted, a complete change of the drawing on the respective sheets is presented.

By taking one of the glass plates away 90 from the mat, different advertising sheets may be arranged to show through the openings 5 in the said mat. It is my idea to use hand drawn and painted cartoons and pictures so that an individual touch is given 95 to each advertisement, which is impossible in the larger field of poster work and which is very much more interesting and clearer than newspaper advertisement. A sufficient space is provided within the cabinet for the 100 reception of the bulbs 9. As a matter of fact, the rear plate need not be of glass, but the frame is to be of a construction to effectively protect the mat and advertising sheets as well as the bulbs from weather conditions. 105

While I have illustrated and described the colored views of different characteristics than the line drawings, I do not wish to be

2
confined to such an arrangement, as both views may be of the same aspect to form a composite view when the bulbs are lighted.

Having described the invention, I claim:—

- 5 An advertising device of the character described comprising a transparency made up of front and rear glass plates, a mat arranged in the rear of the front glass plate and provided with a plurality of differently shaped openings, a translucent sheet arranged between the mat and the rear glass plate respectively and being provided with line drawings and printed matter on its

face with colored views disposed directly to the rear of the line drawings to show there-through in a manner to illustrate the intentional meaning of the line drawing but being of a different subject matter, a frame supporting the plates, mat and sheet in operative position, means carried by said frames for slidably receiving the plates and means for illuminating said transparency for the purpose specified.

15 20
In testimony whereof I affix my signature.

WILLIAM MOUNT BISHOP.
